INTERIOR PARTITION WALL

Frederick M. Venzie, Philadelphia, Pa., assignor
to National Gypsum Company, Buffalo, N. Y.,
a corporation of Delaware

Application January 27, 1934, Serial No. 708,586

8 Claims.

(Cl. 72—46)

My invention relates to building construction, and, more particularly, to a novel interior partition wall formed of fireproof blocks.

Partition walls of this type usually are formed of blocks having square edges. Between all adjoining blocks is a layer of mortar which passes from one side of the wall to the other. In order to increase the rigidity of the wall the blocks are staggered and thus "half blocks" are necessary.

The materials used in such walls are not capable of being reused when the walls are torn down due to the fact that the fireproof and/or soundproof blocks are made of compositions which are so frangible that they will break before the layer of mortar adhering to an entire edge can be hammered off. Obviously such a wall is unnecessarily expensive in those places such as office buildings and apartment houses where partition walls must frequently be erected or torn down to meet the varying space demands of tenants.

The wall embodying the present invention is composed of fireproof blocks arranged in tiers, with studs between adjacent tiers, and means for coupling adjacent tiers together and to the stud and such wall is so formed that the binder between blocks lies only along the corners between the major surfaces and edges of the blocks. Blocks for this purpose may have applied thereto, prior to erection, the finish plaster coat except adjacent the joints.

An object of my invention is to provide a partition wall which may be disassembled readily and without waste so that from the disassembled materials a new wall may be erected.

Another and more specific object of my invention is to provide a wall in which the joints, between the blocks comprising the wall, are not staggered but which is as rigid as the walls in which the joints are staggered, thus providing a wall which may be erected without the use of "half blocks".

A further specific object of my invention is to provide a wall in which the mortar bond between adjacent bricks does not pass from one side of the wall to the other and does not come into contact with supports lying within the wall.

Another specific object of my invention is to provide a block for partition walls which is provided with means for receiving mortar but which blocks are so shaped that they may be erected so that mortar cannot pass through the joints.

Another specific object of my invention is to provide a wall composed of a multiplicity of blocks which when erected carry a final finish and need only be connected by mortar or similar material adjacent their edges and plastered over at such points.

Other and more specific objects of my invention

will be apparent from the following specification, claims, and from the drawing, in which:

Fig. 1 is a vertical elevation of a wall embodying my invention with portions broken away to show the parts therebehind;

Fig. 2 is a horizontal section taken through the wall;

Fig. 3 is a vertical section taken at a joint between two blocks in a wall; and

Fig. 4 is a detailed perspective view of a clip embodied in my invention.

Referring now particularly to the drawing, a floor F, of any preferred construction, herein indicated as of concrete, supports a multiplicity of fireproof blocks or slabs 5 mounted with their vertical edges in alignment. Each of the blocks 5 preferably is formed with a tongue 5a on one horizontal edge and a groove 5b on the opposite edge whereby adjacent blocks may have interengaging horizontal edges. Each of the blocks 5 also is formed with a groove 5c on each of its vertical edges within which is mounted a channel iron 6 with its lower end embedded in the concrete of the floor F and upper end similarly embedded in the ceiling C. Preferably the slot 5c lies within limits of the tongue and groove (Figs. 2 and 3). Prior to its erection the block 5 may also have applied thereto, except adjacent the edges, a finishing coat 12 which preferably may be of plaster. By using units of this type a large amount of time may be saved on the actual construction job and much dirt eliminated.

In order to connect adjacent tiers of blocks 5 a trough shaped clip 7 conforming to the shape of the tongue and groove is mounted over the ends of each of the tongues 5a and this clip extends over the vertical joint between adjacent tiers. In order to mount the clips 7 around channel iron 6, which must necessarily previously have been positioned, each clip is stamped to provide a slot 7a, in one wall 7b thereof, of a size sufficient to allow it to pass around channels 6.

In the web 1c of the clip is cut a slot 7d connecting with the slot 7a and having a width equal to the width of the channel 6. The channel 6 may be held in a predetermined position within the slot 7d by a finger 1e in the web 1c facing the slot 7a, the distance between the sides of the finger and the edge of the slot being such as to exactly fit the flange on one side of the channel 6. From a consideration of Fig. 2 it will be obvious that the channel cannot move out of a vertical plane with respect to the clip when the clip is positioned as shown. In order, however, to slip the clip about the channel, parts of the slot 7d such as indicated at 7m and 7n are cut away to permit the edges of the channel to be moved into their seats. Since these clips are stamped from a continuous strip of metal the clips may be

severed as where desired and as illustrated at the ends of the clip shown may be cut midway of the slot 1d to form means for connecting the end blocks in a wall to a channel without having a part extending therebeyond. After the clip is positioned about the channel iron and on top of the tongues 5a of the blocks 5 it may be secured in place by nails 8 passing through openings 1f in the clip into the blocks 5. Thus the clip provides a means not only for securing the blocks to the channel and preventing movement of one end of two tiers out of a vertical plane, but also a means for preventing longitudinal movement of adjacent blocks away from each other.

15. Each of the blocks 5 carries recesses 10 in each face adjacent the horizontal edge, certain of these recesses 10a being formed at the ends of the horizontal edge and others 10b being spaced from the ends. These grooves are of such depth, 20 relative to the size of the tongues and grooves, that they do not impinge thereon, so that when cementitious material, such as mortar, indicated at 11 is introduced the material does not come into contact with the clip 1, the channel iron 6, or 25 even the tongues and grooves, but lies only a short distance from the face of the block.

Preferably the grooves 5c in the block are of such depth relative to the size of the channel 6 that the blocks 5 will be slightly spaced apart as indicated at 14 (Fig. 2) into which space adjacent the faces of the block a small binder of mortar may be pressed. The space 14, however, should be so small that it is impossible to force the mortar in more than a half inch and in actual practice the depth should normally not be greater than one quarter of an inch. With this small amount of mortar along both the horizontal and vertical edges the blocks may be readily separated when it is desired to demolish the wall, and the 40 mortar, due to the small surface to which it adheres, be easily removed from the block. Should, however, a small part of the block break off adjacent the mortar this would not prevent further use of the block.

45. When the wall is formed with blocks of the preferred type, having the finished coat on most of the major surface, it is necessary only to apply the remainder of the finish coat over the joints in order to have a completed wall. Such procedure saves a large part of the time during which the rooms must remain unoccupied while the plaster is drying. Optionally, where this is not a matter of importance, the blocks need not have the finish coat 12 applied previous to their erection and a complete finish coat may be applied over the entire wall.

Various modifications may be made in the above described embodiment of my invention without departing from the spirit and scope 60 thereof as set forth in the following claims.

What I claim as my invention is:

1. A wall construction comprising a multiplicity of fireproof blocks positioned one on top of another with the edges of adjacent blocks in vertical alignment and a clip conforming in shape to the edges of the blocks positioned between two vertically adjacent blocks and overlying two horizontally adjacent blocks.

70. 2. A wall construction comprising a multiplicity of fireproof blocks positioned one on top of another with the edges of adjacent blocks in vertical alignment, a cementitious binder between por-

tions of the horizontal edges of said blocks; a clip positioned between two vertically adjacent blocks and overlying two horizontally adjacent blocks; and means for fixedly connecting horizontally adjacent blocks to said clips.

3. A wall construction comprising a multiplicity of fireproof building blocks positioned side by side with the edges of adjacent blocks in alignment both vertically and horizontally considered; a tongue on one horizontal edge of said block and 10 a groove on the adjacent horizontal edge of an adjoining block; a groove in the vertical edges of each block; a channel iron, fixed to supports above and below said wall, in said grooves; a clip fixed to the tongues on adjacent blocks and overlying 15 the vertical joint therebetween, said clip comprising means to connect said blocks to said channel iron; longitudinal recesses in said block where the faces meet the horizontal edges adjacent the vertical edges and also spaced from said vertical edges, said recesses also being spaced from said tongues and grooves; a cementitious composition filling said recess and connecting said blocks; and a finishing material over the whole.

4. A wall construction comprising a multiplicity 25 of fireproof building blocks positioned in adjacent tiers; means for breaking the horizontal joint between adjacent blocks in a tier; a groove in the vertical edges of each block; a support in said grooves fixed above and below said wall; a clip 30 connecting adjacent tiers, said clip also comprising means to connect said blocks to said channel iron; longitudinal recesses in said block where the faces meet the horizontal edges adjacent the vertical edges and also spaced from said vertical 35 edges; a cementitious composition filling said recess and connecting said blocks; and a finishing material over the whole.

5. A wall construction comprising a multiplicity of fireproof building blocks positioned in tiers side 40 by side; a groove in the vertical edges of each block; a channel iron, fixed to supports above and below said wall, in said grooves; and a clip fixed to the tongues on adjacent blocks, providing 45 means to connect said blocks to said channel iron.

6. A wall construction comprising a multiplicity of fireproof building blocks positioned side by side both vertically and horizontally considered with their edges in abutting relationship; a tongue on one horizontal edge of said block and a groove on 50 the adjacent edge of an adjoining block; a riser, fixed to supports above and below said wall, lying between and within adjacent blocks; a clip, fixed to the tongues on adjacent blocks, and conforming to the shape of said tongues, said clip providing means to connect said blocks; and means for receiving a cementitious material between adjacent edges of said blocks but maintaining it out of contact with said tongue and groove, riser and 55 clip.

7. A wall construction comprising a multiplicity of fireproof blocks arranged in tiers and courses, a vertical support between adjacent tiers and means positioned between adjacent courses and lying between the surfaces of the wall connecting 60 said blocks to said support.

8. A clip comprising means engaging the face and both edges of a tongue on a building block, and means incised in the tongue engaging portion 70 of said clip engaging a support.

FREDERICK M. VENZIE.
